ATTORNEYS

UNITED STATES PATENT OFFICE.

GUSTAV EY, OF NEW YORK, N. Y.

CORNER-BLOCK MOLD.

Application filed October 30, 1925. Serial No. 65,858.

To all whom it may concern:

Be it known that I, GUSTAV EY, a citizen of the United States and a resident of the city of New York, borough of Manhattan, 5 in the county of New York and State of New York, have invented a new and Improved Corner-Block Mold, of which the following is a full, clear, and exact description.

10 This invention relates to block molds and was primarily designed for use in making concrete corner blocks.

In molds constructed with miter joints a great deal of difficulty is experienced in 15 fitting the molds together after they have been used for some time due to the fact that a certain amount of concrete or the like adheres to the molds. If the molds with miter joints are fitted together with concrete adhering to them the members are likely to be thrown out of proper alinement and the result will be blocks that are not accurately shaped. Other types of molds are constructed and the transverse members are attached to the longitudinal members by fitting a plate on one into a slot formed in the other. This construction is also unsatisfactory because the slots are continually blocked by the concrete.

20 The general object of this invention is the provision of a simple and efficient mold so constructed that the members may be quickly assembled and disassembled.

A further object of the invention is the 25 provision of a mold, the members of which are provided with simple means for connecting them together, the connecting means being so constructed that the deposits of concrete or the like do not cause any great 30 amount of trouble or the possibility of disalinement resulting in improperly shaped blocks.

Another object of the invention is the provision of a mold, the members of which 45 are formed with straight sides thus introducing cheapness of manufacture and simplifying the replacement of worn and destroyed parts.

A still further object concerns the provision of a mold by means of which a simple and efficient corner block can be 50 readily cast.

The invention is illustrated in the drawings, of which Figure 1 is a perspective 55 view of the block formed in this mold.

Figure 2 is a plan view of a plurality of mold sections assembled.

Figure 3 is a plan view showing various 60 portions of one mold section laid out flat side by side.

Figure 4 is a section taken on the line 4-4 of Figure 2; and

Figure 5 is a section taken on the line 5-5 of Figure 2.

The form of the invention shown in the 65 drawings is a preferred form, although it is understood that modifications in the construction and arrangement of the parts and in the character of the materials used may be adopted without departing from the 70 spirit of the invention as set forth in the appended claims.

In its general aspect the invention comprises a plurality of longitudinal wall members having hollow longitudinal beadings 75 therein, these beadings have preferably straight sides. There are also preferred transverse wall members likewise provided with hollow straight-sided beadings extending longitudinally thereof. The transverse 80 members are provided with notches in the ends thereof permitting them to be fitted over the beadings on the longitudinal members. Preferably suitable guides are mounted on the beadings of the longitudinal wall 85 members to assist in gradually locating the transverse members. In order to form a corner block I also provide a hollow core member which is disposed parallel to the longitudinal wall members placed a desired 90 distance therefrom, as will be hereinafter described. This core member is employed and acts to close up one end of the hollow beadings on the transverse wall members to prevent concrete from flowing thereinto. 95

In the preferred form of the invention which is shown in the drawing, I desire to form a block having side walls 10 and 11 and an end wall 12. The side walls are to be connected by the web 13, which is connected to the side walls by means of bracing members 14, 15, 16 and 17. Between one end of the web 13 and the end wall 12 is an opening which permits a block to be readily grasped in the hand by passing the fingers 100 through said opening to grip the adjacent end of the web. This opening also acts as a passageway for reinforcing elements when the block is arranged in vertical alinement with other blocks in the wall. 110

To form such a block I provide a mold member with longitudinal wall elements such as 18 and 19. These wall members, on one side thereof, are provided with hollow beadings such as 20, having straight sides and open ends. Mounted on the front faces of the hollow beadings are guide members such as 21 in the form of spring fingers which assist in locating certain transverse elements.

Adapted to extend across between the longitudinal wall members 18 and 19 are transverse wall members 22, 23 and 24. These are provided on their side faces with hollow beadings such as 25. One end of each of these transverse members or walls are provided with grooves or cut-out portions 26, whereby they may fit over the hollow beadings on the longitudinal wall member 18. On the other end of the hollow beadings 25 are disposed guide members 27 of the type above mentioned. These guide members 27 are adapted to engage with the open ends of hollow core members 28 which extend across between the transverse wall members 22, 23 and 24 to form the aperture in the block above mentioned. These core members also are formed and disposed to close the open ends of the beadings 25, as is clearly shown in the drawings. Bottom plates 29 and 30 are provided and assembled as shown.

In accordance with the assembly shown in Figure 2, the longitudinal members 18 provides an end wall for each section and for each block form, the beading of this end member forming the end groove in the block. The beading on the transverse members form the longitudinal grooves in the block. The core members extending across between the transverse members form the apertures found in the block between the end wall and the end of the wall. The open space between the core members and the lower longitudinal wall members seen in Figure 2 forms the end wall 12. The open space between the beadings 25 mounted on the transverse wall members forms the web. The slope of the

beadings form the bracing members above mentioned. The elements are assembled as shown in Figure 2 and may be held together by any suitable means not shown. In this construction the fact that all the elements used have straight sides permits the device to be manufactured economically, and the fact that they all fit tightly together, lacking any openings, will prevent the concrete from settling and causing trouble in the proper alignment of the parts.

What I claim is:

1. A corner block mold which comprises longitudinal transverse wall members, hollow beadings mounted on said members and running longitudinally thereof, the beadings on the transverse members adapted to abut the beadings on one of the longitudinal wall members, and a hollow core member extending between the transverse members and lying adjacent the other ends of the beadings therein.

2. A corner block mold which comprises transverse and longitudinal wall members, means for adjustably holding them in their relative positions, and hollow beadings on one side of the longitudinal wall members, hollow beadings on the transverse members abutting the beadings on said longitudinal wall members at one end. A hollow core member extending between the transverse members and abutting the other ends of the beadings on said transverse members, said core member being spaced from the other longitudinal members to provide a space in which an end wall for said block is formed.

3. A corner block mold which comprises longitudinal and transverse wall members, hollow beadings formed therein, a hollow core member extending between said transverse members, said core member being spaced from one of said longitudinal members to provide space for the formation of an end wall and means on said transverse and longitudinal members to hold the parts temporarily in their relative positions.

GUSTAV EY.
